Primary Examiner — Doris Clark(74) *Attorney, Agent, or Firm* — Alexander H. Plache; Abel Law Group, LLC(57) **CLAIM**

We claim the ornamental design for a frame assembled in a manufactured panel, as shown and described.

DESCRIPTION

FIG. 1 is a front perspective view of a frame assembled in a manufactured panel.

FIG. 2 is a rear perspective view thereof.

FIG. 3 is a left side view thereof.

FIG. 4 is a rear view thereof.

FIG. 5 is a front view thereof; and,

FIG. 6 is a right side view thereof.

The broken lines are for illustrative purposes only and form no part of the claimed design.
